VENDING MACHINE

Frank C. Burge, Dallas, Tex.

Application May 6, 1941, Serial No. 392,037

6 Claims. (Cl. 312—66)

This invention relates to merchandise vending machines and it has particular reference to coin operated machines for vending packaged merchandise or fresh fruits such as apples, oranges and the like.

The principal object of the invention is to provide a vending machine in which the merchandise is compactly stored in grouped, vertically disposed magazines preparatory to being discharged singly from a selected magazine. Moreover, the merchandise storage magazines being relatively independent, articles of merchandise of different brands or specie may be stored in the magazines according to their particular brand or specie and so dispensed.

Another object of the invention is to provide for individual mounting of the merchandise magazines in the machine in order that when one or more of such magazines are depleted of merchandise, the empty magazine or magazines may be removed from the group and refilled without interfering with the companion units.

Another object of the invention is to provide a common cooperating means for suspending the column of merchandise in a magazine while the lowermost article in the column is being simultaneously ejected from the machine. Furthermore, the operating mechanism of the machine including means actuated by an adjacent magazine when one magazine has been manually manipulated to the discharging station, for releasing the ejector mechanism for operation.

Still another object of the invention resides in the provision of means for prohibiting the insertion of a coin or token into the machine until a selected magazine has been disposed operatively at the discharging station.

With the foregoing objects as paramount, the invention consists of other objects and structural features of accomplishment, illustrated in the accompanying drawing, wherein:

Figure 1 is an elevational view of an embodiment of the invention partly in section and partly broken away.

Figure 2 is a transverse section on line 2—2 on Figure 1.

Figure 3 is a transverse section on line 3—3 on Figure 1.

Figure 4 is a vertical sectional view of the base per se, taken on line 4—4 of Figure 3 showing the operating mechanism of the machine.

Figure 5 is a detail view of the coin actuated means for releasing the ejector mechanism for operation.

Figure 6 is a fragmentary view of the under-

side of the base, taken on line 6—6 on Figure 4 to show the ejector control ratchet and pawl.

Figure 7 is a fragmentary detail view of the base showing the coin resisting slide, and

Figure 8 is a fragmentary detail view of the means for operatively connecting the dome of the machine with the magazine assembly for common rotation.

Continuing with a more detailed description of the drawing, reference is primarily made to Figure 1 wherein is shown the base 10 of the machine, provided with bosses 11 (Figure 4) by which it may be secured to a stand or counter. Disposed on top of the base 10 is an annular flange 12 for retaining a cylindrical shell or casing 13 of glass or other transparent material.

Extending vertically through the center of the base 10 and upwardly through the casing 13 is a shaft 14. This shaft is anchored at its lower end by a cross-member 15 (Figure 4) and its upper end extends through an opening in the dome 16 which latter rotates around the shaft which is stationary. A circular plate 17 is mounted above the dome and rests on a shoulder 18 on the shaft. An aperture is made diametrically through the shaft near its upper end to receive the bow of a lock 19, the latter resting on the plate 17 which, in view of its free mounting, does not revolve with the dome. Thus, the dome is held in operative relationship with the casing 13 and cannot be displaced without authority.

Grouped about the shaft 14 are a plurality of vertically disposed merchandise magazines 20, held in radially spaced relationship and in suspended relation to the base 10 by means of spiders 21. The spiders have central openings to receive the shaft 14 and are spaced apart by rods 22. A collar 23 surrounds the shaft 14 and is disposed below the lowermost spider to support the assembly. A set screw 24 holds the collar securely on the shaft.

It is intended that the magazines 20 be independently removable from the machine for refilling or for other purposes, such as substitution of magazines of different cross-sectional shape. To accomplish this, each magazine has a dovetailed, elongated protuberance or rib 25 extending longitudinally along its rear surface. These ribs are receivable in correspondingly shaped recesses radially spaced about the perimeters of each of the spiders 21 as exemplified particularly in Figure 2. In order to remove a magazine, it is necessary only to remove the lock 19, plate 17 and the dome 16.

and lift the magazine upward to withdraw the rib 25 from the retaining recesses of the spiders 21.

The dome 16 is welded, as shown, or otherwise suitably affixed to and is therefore supported through the medium of a tubular sleeve 26 on the uppermost of the spacing spiders upon which it rests, the sleeve being disposed around the shaft 14. The lower end of the tubular sleeve 26 is diametrically slotted to straddle a pair of upstanding lugs 27 (Figure 8) cast integral or fixed to the upper face of the top spider. Thus, when the dome 16 is rotated, this motion is imparted to the magazine assembly and by grasping one of the several knobs 28, each in alignment with a magazine 20, an operator may manipulate the assembly to bring a selected magazine to a stop at the discharge station or in register with the discharge opening 29 preparatory to vending an article of merchandise.

Until a magazine is in position to vend, the coin receiving slot 30 (Figures 4 and 7) is covered by a slide 31.

Movement of this slide to uncover the coin slot is effected by means of the arrangement shown in Figure 7, and which consists of a plunger or detent 32 which extends through the base and lies in the path of the magazines 20 as they are rotated. A spring 33 holds the detent 32 in raised position and is collapsed when the detent is depressed by contact therewith of a shoe 34 (Figures 1 and 7) carried by the underside of each magazine 20. When the detent is thus depressed, a bell crank 35 is moved on its pivot *a* by a pin 36 carried by the stem of the detent 32 and the bell crank, being pivoted at *b* to the slide 31, causes the latter to move from its position over the coin slot 30. A spring 37 returns the slide to its operative position over the slot when the detent is released by further movement of the magazine assembly.

The merchandise discharging or ejecting mechanism consists of a slide 38 held by channels 39 for sliding movement diametrically across the floor of the base and an upturned portion 40 on its outer end serves as a door or closure for the discharge opening 29. A handle 41 is mounted on the closure for operating the slide.

Disposed intermediate the ends of the slide 38 is a pair of uprights 42 and adjustably mounted in each is a horizontally disposed pin 43, the pair of pins being directed toward the merchandise discharge station or opening 29.

Immediately below these pins, and mounted on a threaded pin 42a, is an ejector 44. The pin 42a, by virtue of its threaded connection to a U-shaped support 42b, is axially adjustable, the latter being in turn, supported by pins 42. The ejector 44 consists of a concave rubber disc adapted to engage and thrust outward the lowermost article of merchandise in the column disposed in a magazine when the slide 38 is pulled outward. At the same time, the pins 43 engage between the lowermost and the next succeeding article of merchandise to thereby support the column while the bottom article is being discharged. To facilitate discharge, a plate 45 is disposed next adjacent to and secured to the closure 40 of the slide and inclined transversely thereto and as the latter is withdrawn, the ejected article will, due to the incline, be propelled into a receiving receptacle 46 attached to the base 10 to one side of the opening 29.

The control means for the slide 38 consists of a depending rod 47 extending through a slot 48 in the base parallel with and offset with respect

to a longitudinal slot 49 (Figure 4) in the slide 38 through which the central shaft 14 passes. Affixed to the underside of the base is a rack bar or ratchet 50 and cooperating with the teeth of this bar is a pawl 51 which being mounted in a spring controlled collar 52, is capable of oscillation with respect to the rod 47 on which the collar is rotatably mounted. A spring 53 connects the rod 47 with the base in order that the slide 38 to which the rod 47 is attached, will be returned to its original position after each vending operation.

Further reference to the rack and pawl will be made in the course of the description of operation.

In Figure 5 is illustrated the coin controlled means which places the mechanism in vending position. This means consists of a coin receiver 54 shown with its cover plate removed and whose coin recess 55 communicates with the coin chute 56. A plunger 57 is vertically and slidably disposed in a groove in the receiver 54 with one end 58 passing through the base and entering a slot 59 in the slide 38 (Figure 4), thereby locking the slide against movement. A leaf spring 60 bears against the lower end of the plunger to hold the same in locking position.

To overcome the resistance of leaf spring 60 and to retract the plunger 57, an arm 61 slidably enters the coin receiver 54 and has its opposite end pivoted to the depending rod 47. The free end of the arm is curved to conform to the contour of a coin 62 and when in the position shown in solid lines in Figure 5 the coin serves as a rigid connection between the arm 61 and the beveled edge 63 of a recess in the plunger 57. Thus, it will be seen that as a pull is exerted on the slide handle 41, pressure imposed axially on the arm 61 by the depending rod 47 will be transmitted to the coin 62 and bearing on the beveled portion 63 of the plunger 57, the coin will urge the latter downward, its upper end being thereby retracted from the slot 59 in the slide 38, releasing the latter. Midway between the top and bottom of the coin recess 55, a pair of projections 63a are affixed to and extend outwardly from the receiver 54 on each side of plunger 57 to lie above the line of travel of the arm 61. These stops prevent the coin 62 from sliding upon the beveled end of arm 61 when the latter is operated.

In operation, the knobs 28 are employed to manipulate a selected magazine 20 into a position for vending and when so disposed, an adjacent magazine will be in a position so that its shoe 34 will depress the detent 32. This action will displace the coin resisting slide 31 to admit a coin into the slot 30. The coin falls into the recess 55 of the receiver 54 and a pull upon the handle 41 will urge the coin in the direction of the arrow in Figure 5 and in being so displaced, the coin will actuate plunger 57 to release the slide, allowing it to be pulled out and with it the lowermost article of merchandise in the selected magazine. The article will be deposited in the receptacle 46. As the slide is pulled out, the pawl 51 drops into successive teeth of the ratchet 50, preventing return of the slide through the action of spring 53 until the slide has been moved to its extreme outward position whereupon the pawl changes positions and will have no effect to further hold the slide.

It is understood of course that while the transverse cross-section of the merchandise magazines is circular for retaining spherical articles such

as apples, oranges and the like, limitation as to shape of these elements is not intended.

Manifestly, the construction as shown and described is capable of some modification and such modification as may be construed to fall within the scope and meaning of the appended claims is also considered to be within the spirit and intent of the invention.

What is claimed is:

1. A vending machine comprising a base and a plurality of radially grouped merchandise magazines rotatably disposed thereover, a transparent case having a discharge opening, a dome rotatably disposed on said case and connected to said magazines to rotate the same, a merchandise vending slide mounted on said base and movable through said discharge opening, parallel pins vertically mounted on said slide, fingers horizontally mounted for axial adjustment on said pins, means also carried by said pins for ejecting an article from a column of merchandise in a selected magazine, when said slide is moved outwardly, said fingers supporting the column during the vending operation, means to prevent retraction of said slide during the vending operation, and means for returning said slide to its inoperative position subsequent to the vending operation.

2. In a vending machine, a base, a casing disposed thereon having a discharge opening, a series of merchandise magazines rotatably disposed above said base, each being alignable with said discharge opening, a vending slide on said base and movable through said discharge opening, a pair of pins mounted on and perpendicular to said slide, an article ejector carried thereby, a merchandise support also carried by said pins for suspending the column of merchandise during ejection of an article from a magazine, means for holding said slide against retraction during a vending operation and means for retracting said slide subsequent to the vending operation.

3. A structure as set forth in claim 2 in which the vending slide is substantially flat, a deflecting plate upon which an article of merchandise is deposited from a merchandise magazine for propelling the same sidewise from said slide and means for receiving said article of merchandise.

4. In a vending machine, a base, a group of interconnected merchandise magazines radially and rotatably disposed above said base, a transparent casing surrounding said magazines, having a discharge opening therein, a merchandise vending slide movable through said opening, an

inclined plate carried by said slide for directing discharged merchandise laterally with respect thereto, a receptacle for discharged merchandise, parallel, upright pins mounted on said slide and perpendicular to said base, means supported by said pins and adjustable axially for ejecting articles of merchandise singly from selected ones of said magazines aligned with said discharge opening, means also supported by said pins and likewise axially adjustable for supporting the column of merchandise remaining in said magazine during a vending operation and means for holding said slide against retraction during said vending operation.

5. A merchandise vending machine comprising a base, a vertical shaft mounted on and rising above said base, spaced spiders on said shaft, a plurality of vertically disposed, radially grouped merchandise magazines mounted on said spiders and rotatable above said base, a dome connected to said magazines for rotating the same, a transparent, cylindrical shell embracing said magazines, a merchandise discharge slide, relatively spaced, vertically disposed pins mounted on said slide, means carried by said pins and adjustable axially for ejecting the lowermost article of merchandise in selected ones of said magazines, cooperating means on said pins for projecting under and sustaining the remaining merchandise in a magazine during the vending operation, means for preventing retraction of said slide during the vending operation and means for returning said slide subsequent to the vending operation.

35 6. A vending machine comprising a base and a series of vertically and radially grouped merchandise magazines situated above said base for rotation, a transparent stationary casing for said magazines having a common discharge opening, means for manually rotating the group of magazines, a member slidably on said base and movable through the opening in said casing, a closure carried by said slide to cover said opening, vertically disposed pins mounted on said slidably member, an axially adjustable merchandise ejector carried by said pins for singly discharging articles from selected magazines, means also carried by said pins engageable under and supporting the remaining merchandise in a selected magazine during a vending operation, means holding said slidably member against return during the vending operation, and means for returning said member to its original position subsequent to the vending operation.
